ELECTROCARDIOGRAPHIC RECORDING HOLSTER

Joseph A. Hesen, Torrance, Calif., assignor to Cardiac
Scan Service, Inc., Los Angeles, Calif.

Filed May 28, 1974, Ser. No. 473,815

Term of patent 14 years

Int. Cl. D24—02

U.S. Cl. D83—1 F

FIG. 1 is a front perspective view of an electrocardiographic recording holster showing my new design; and FIG. 2 is a rear perspective thereof.

I claim:

The ornamental design for an electrocardiographic recording holster, as shown.
